(57) **CLAIM**

The ornamental design for a towel dispenser, substantially as shown and described.

DESCRIPTION

FIG. 1 is a front, raised perspective view of a towel dispenser according to a first embodiment of the invention; FIG. 2 is a front view of the towel dispenser of FIG. 1; FIG. 3 is a rear view of the towel dispenser of FIG. 1; FIG. 4 is a right side view of the towel dispenser of FIG. 1; FIG. 5 is a left side view of the towel dispenser of FIG. 1; FIG. 6 is a top view of the towel dispenser of FIG. 1; FIG. 7 is a bottom view of the towel dispenser of FIG. 1; FIG. 8 is a front, lowered perspective view of the towel dispenser of FIG. 1; FIG. 9 is a front, raised perspective view of a towel dispenser according to a second embodiment of the invention, the second embodiment being similar to the first embodiment but with a transparent lower section; and, FIG. 10 is a front, lowered perspective of the towel dispenser of FIG. 9.

The dashed broken lines in the drawings show environmental structures and form no part of the claimed design.

1 Claim, 10 Drawing Sheets
